UNITED STATES PATENT OFFICE.

JOHN D. IHLDER, OF NEW YORK, N. Y., ASSIGNEE TO OTIS ELEVATOR COMPANY, OF JERSEY CITY, NEW JERSEY, A CORPORATION OF NEW JERSEY.

ELECTRICAL CONTROLLING APPARATUS.

1,156,481.

Specification of Letters Patent.

Patented Oct. 12, 1915.

Application filed August 5, 1913. Serial No. 718,370.

To all whom it may concern:

Be it known that I, JOHN D. IHLDER, a citizen of the United States, residing at New York, in the county of New York and State of New York, have invented a new and useful Improvement in Electrical Controlling Apparatus, of which the following is a specification.

My invention relates to a system of electric motor control in which a stop magnet or load magnet as it is sometimes termed, automatically operates during the slowing down of the motor to introduce a variable amount of resistance in a dynamic circuit, 10 the amount of said resistance placed in the circuit varying inversely as the speed of the motor, to effect a substantially uniform slowing down and stopping of the motor with varying loads. The controlling mechanism comprises a manually operable switch for controlling the slowing down and stopping of the motor, and also automatic stop motion mechanism to effect such operation at a predetermined period or periods. An 20 object of my invention is to provide means automatically to control the load magnet and cause an independent dynamic braking action when the stop motion mechanism operates, than when the slowing down is effected through the operation of the manual switch.

The accompanying drawing is a diagrammatic illustration of a system of electric motor control embodying my invention, the 30 particular form of mechanism herein shown being adapted for use in an elevator system.

The apparatus as shown comprises a main line switch D, a potential switch P, a manual car switch or controller K, reversing switches R and R', an accelerating magnet E controlling a sectional starting resistance H, and a series field winding F, a shunt field S, limit switches L', L'', a speed governor G, a car safety switch I; all of which 40 may be of usual or well-known construction. The load magnet L controls resistance placed in series with or used without an extra field winding O, adapted to be connected in a circuit across the brushes of the 45 motor armature M. The reversing switch R comprises a magnet coil 1, a magnet core 50 carrying upper contacts 2 and 3, movable into engagement with stationary contacts 4 and 5, respectively, when the magnet is energized, and lower contacts 6 and 7 movable into engagement with stationary contacts 8 and 9, respectively, when the magnet core is dropped. The construction of the reversing switch R' is similar. The two magnets are preferably interconnected by a 55 lever or other suitable means to prevent both sets of back or lower contacts being closed at the same time.

Current is supplied from any suitable source to the mains designated + and -, respectively.

The potential switch P is held closed by its own magnet during the normal operation of the apparatus. The circuit for the potential switch magnet may be traced from 70 the positive main through the main line switch D, conductors 11, 12, through both blades of the car safety switch I, conductor 13, potential switch magnet coil 14, conductor 15, governor switch 16, upper and lower 75 limit switches L', L'', conductors 37, 16', potential switch contacts 17, and through the switch D to the negative main.

To start the car in an upward direction, the lever of the car switch K is moved to 80 the left, to bring the segmental contact 18 into engagement with the stationary contact 19. This completes a circuit through the magnet coil 1 of the reversing switch R as follows: from the positive main, through 85 conductors 11, 12, car safety switch I, conductor 21, switch contacts 22, 18, 19, conductor 23, reversing switch coil 1, conductor 24; contacts 25 of the stop motion switch, conductor 26 to the junction 27. At this point 90 the circuit branches; one lead extending through a resistance 28 to the junction 29, and the other lead extending through contacts 32 and 31 of the stop motion switch, conductor 33, magnet coil 34, conductor 35, 95 back contacts 36 of the load magnet L, and to the junction 29. From thence the circuit continues through conductors 37 and 16', potential switch contacts 17, and thence to the negative main. The reversing switch R 100 is therefore operated to connect the contacts 2, 4 and 3, 5, thereby establishing the fol-

lowing circuits: The motor armature is connected to receive current through a circuit from the positive main, through conductor 11, potential switch contacts 10, conductor 20, series field windings F, starting resistance H, conductors 38, 39, back contacts 40, holding coil 41, conductor 42, to brush 43 of the motor armature. From the opposite brush 44 the circuit continues through conductors 45, 46, back contacts 47, conductors 48, 49, switch contacts 2, 4, conductor 50, potential switch contacts 17, and to the negative main. A circuit across the armature brushes is also completed as follows: from the brush 43, through conductor 42, holding coil 41, back contacts 40, conductors 39, 38, 51, back contacts 52 of the fast speed magnet FS, conductor 53, resistance N, extra field coil O, conductor 54, back contacts 47, conductors 46 and 45, to the brush 44. A circuit through the shunt field S may be traced from the positive main, through conductor 11, contacts 10, conductors 20, 55, shunt field S, conductors 54, 48, 49, contacts 2, 4, conductor 50, contacts 17, and to the negative main. A circuit for the electromagnetic brake is completed from the positive main, through conductor 11, auxiliary contacts 56 of the potential switch, conductor 57, winding 58 of the brake magnet, conductor 59, auxiliary contacts 60, conductor 61, auxiliary contacts 62, 63, carried by the reversing switch R, conductor 49, contacts 2, 4, conductor 50, and thence to the minus main. The brake magnet being energized, the brake is lifted and the motor permitted to start. The motor starts with a powerful field as the series field, shunt field and extra field windings are all receiving current.

The continued movement of the car switch lever to the left brings the contact 18 in engagement with the stationary contact 64. This completes a circuit through the fast speed magnet winding as follows: from the positive main, through conductors 11, 12, switch I, conductor 21, controller contacts 22, 18, 64, conductor 65, contacts 66, conductor 67, winding 68 of the fast speed magnet FS, conductor 69, back contacts 36, conductors 37, 16'; contacts 17 and to the minus main. The fast speed magnet therefore operates with the following results: A section 70 of the starting resistance is short-circuited through the contacts 71 of the fast speed magnet, thereby permitting the motor to accelerate. The accelerating magnet E is connected across the motor armature in a circuit from the brush 43, through conductor 42, coil 41, contacts 40, conductors 39, 38, 51, contacts 71, section 74 of the starting resistance, conductor 75, contacts 76, conductor 77, winding of the accelerating magnet E, conductors 78, 49 and 48, contacts 47, conductors 46 and 45, to the brush 44. The

accelerating magnet therefore receives current in proportion to the speed of the motor and operates in a well-known manner to successively short-circuit the remaining sections of the starting resistance H and series field F, thereby bringing the motor up to normal speed. The operation of the fast speed magnet FS also separates the contacts 52, thereby opening the extra field circuit and weakening the motor field, prior to the 75 operation of the accelerating magnet.

The stop motion switch mechanism comprises a number of cams A, B and C, which are adapted to be operated automatically in the order named to effect a slowing down 80 and stopping of the motor independently of the car switch K. This stop motion switch mechanism when used in elevators is ordinarily arranged to operate automatically as the car nears either limit of travel when for 85 any reason the manual switch K has not been operated at the proper time or fails to stop the car.

The operation of slowing down when the stop motion switch mechanism is brought 90 into action is as follows: The cam A first operates to separate either the contacts 66 or 66'. If the car is going up the contacts 66 will be separated, thereby opening the circuit of the fast speed magnet which drops 95 its core and operates to reduce the motor speed by opening the circuit of the accelerating magnet E and introducing the starting resistance and also the series field F into the armature circuit. At the same time the 100 back contacts 52 again complete the extra field circuit and thereby further retard the motor. The cam B next operates to separate the switch contacts 32. This opens the circuit through the auxiliary load magnet 34 105 and permits the contacts 79 to come together and establish a circuit through the load magnet L. This circuit which is across the motor armature may be traced from the brush 43, through conductor 42, coil 41, 110 contacts 40, conductors 39, 38, 51, contacts 52, conductor 53, magnet coil L, contacts 79, conductors 85, 86, auxiliary contacts 63, conductors 82, 49; 48, contacts 47, conductors 46, 45, to brush 44. The function and operation of the load magnet are fully set forth in my patent for improvements in elevators, No. 710,581, October 7, 1902, and need only be briefly referred to here. The load magnet L being energized, operates to 115 lift one or more of the contacts a, b, c, thereby short-circuiting an amount of the extra resistance N proportional to the speed of the motor. The contacts a, b and c which constitute the armatures for the magnet L 120 are placed at different distances from the magnet or otherwise arranged to operate in succession and for different degrees of strength of the magnet L. If, for example, there is a comparatively light load and a cor- 125

130

respondingly high speed of the motor, a larger proportion of the resistance J will be short-circuited with a corresponding increase of current in the main line and the extra field O . If, on the other hand, the load is heavy and the speed of the motor slow, a smaller amount of the resistance will be short-circuited and the main line and extra field will receive less increase of current. As a result the speed of the motor may be reduced to any predetermined amount independently of variations in the load.

It should be noted that in the operation of the automatic stop motion as above described the operation of the cam A effects a variable reduction in speed before the cam B acts. The cam B then causes the load magnet L to be connected directly across the motor armature through the circuit above traced, closing more or less of the contacts and thereby reducing the speed for varying loads to the predetermined amount. When the load magnet circuit is completed, as above described, the reversing switch magnet is still energized and the reversing switch is not yet opened. The resistance 28 in the branch circuit maintains a circuit for the reversing switch magnet at this time.

The cam C next operates to separate the contacts 25 in the circuit of the reversing switch magnet so that the reversing switch is opened to cut off the current supply and to permit the electro-mechanical brake T to be applied.

The normal slowing down operation which is effected by the manipulation of the manual controller K , is substantially different from that due to the automatic mechanism above described. One of the differences involved is the introduction of the resistance 80 in circuit with the load magnet L , the purpose and operation of which will be fully stated later.

When the operator desires to slow down and stop the motor, the car switch K is moved back to central position. As the contact 18 runs off the contact 64 , the circuit through the fast speed magnet is broken, so that said magnet drops its core, thereby operating to reduce the speed of the motor as above explained in connection with the automatic stop mechanism. The load magnet L does not operate until the reversing switch circuit is opened as the contacts 79 in the circuit of the magnet L are held apart by the auxiliary load magnet 34 in series with the reversing switch magnet.

When the controller contact 18 moves off the contact 19 the circuit through the reversing magnet and the auxiliary magnet coil 34 is opened, closing contacts 79 , and the reversing switch R opens, thereby cutting off the current supply. The contacts 79 brought together complete a circuit through the load magnet L , across the motor ar-

ture. This circuit may be traced from the brush 43 , through conductor 42 , holding coil 41 , contacts 40 , conductors 39 , 38 , 51 , contacts 52 , conductor 53 , load magnet L , contacts 79 , a resistance 80 , conductors 81 , 82 , 49 , 48 , contacts 47 , conductors 46 , 45 , to brush 44 . The load magnet L being energized operates as before described to short circuit more or less of the resistance N , but in the present instance the resistance 80 is introduced in the magnet circuit which results in a less powerful action of the magnet.

This is an important feature of my invention. The purpose and effect of this arrangement will be readily understood when it is considered that the lever of the controller K is usually thrown quickly to "off" position, often while the motor is running at full speed. The potential of the load magnet circuit, that is, across the armature brushes, is therefore higher than in the case of the automatic stop where the cam A operates to reduce the motor speed, before the load magnet circuit is established. The operation of the load magnet without the resistance 80 would therefore be too severe in the manual control and more powerful than in the operation of the automatic stop mechanism.

By introducing the resistance 80 the strength of the load magnet is kept down which results in a gentle and smooth stopping of the motor and elevator car. The automatic stop motion mechanism is in the

nature of an emergency device, which is occasionally brought into operation, and when it does operate, a comparatively powerful action of the load magnet is required to bring the car to the required slow speed in the short length of travel permitted after the automatics begin to operate. My invention permits the use of a load magnet having sufficient power to cause this quick automatic stop, and also permits a gentle and easy stopping of the car under manual control, whereas without the use of the resistance 80 , the load magnet would either cause a harsh and abrupt stop of the car when under control of the operator, or the magnet must be too weak to effect a satisfactory emergency stop.

The load magnet is designed and adjusted to properly control the automatic stopping of the motor, and the resistance 80 is then adjusted to moderate the action of the magnet to any extent desired in manually controlling the stopping at intermediate floors.

The operation of the controlling apparatus in starting the load device in a downward direction, and in slowing it down during the downward travel is substantially the same as that already described in connection with the upward travel of the load device. The lever of the controller K is moved to the right to start the car downward. This completes a circuit through the

magnet for the reversing switch R' and the latter operates to establish a circuit through the motor armature in the reverse direction from that of the upward travel.

5 It will be understood that my invention is adapted for use with various forms of controlling apparatus other than that herein disclosed, and comprehends such modifications as come within the scope of the 10 pended claims. I wish therefore not to be limited to the precise construction and arrangement of apparatus disclosed.

What I claim is:-

1. The combination of an electric motor, 15 slow down mechanism operable to apply a retarding action to the motor proportional to the speed of the motor, a manual device for effecting the operation of said slow down mechanism, and automatic means to effect 20 a modified operation of the slow down mechanism.

2. The combination of an electric motor, 25 controlling apparatus therefor comprising manually controlled means automatically operable to effect a slowing down action on the motor proportional to the motor speed, and automatic mechanism to cause said slowing down means to produce a more powerful slowing down action also in proportion 30 to the motor speed.

3. The combination of an electric motor, 35 controlling mechanism therefor comprising an extra field circuit, resistance in said circuit, an electromagnet controlling said resistance, circuits for said electromagnet in parallel with the motor armature, and containing different amounts of resistance, and separate means for establishing said electromagnet circuits during the slowing down of

the motor, one of said means being controlled manually.

4. The combination of an electric motor, 45 controlling mechanism therefor comprising a load magnet, resistance controlled thereby in a circuit of the motor, manually controlled means for establishing a circuit through the said magnet in slowing down the motor, and means to introduce resistance into said magnet circuit, and thereby effect a modified slowing down operation. 50

5. The combination of an electric motor, 55 controlling mechanism therefor comprising a load magnet, means controlled thereby to effect a reduction of the motor speed, resistance, a manual lever operable to effect the completion of a circuit through the load magnet and said resistance, and means operable independently of the manual lever to establish a circuit through the load magnet independently of said resistance. 60

6. The combination of an electric motor, a manual controller, an automatic controller, a load magnet, resistance controlled thereby, a resistance adapted to be placed in circuit with the load magnet, to establish 65 said circuit through the load magnet and said last named resistance when the manual controller is operated, and means to establish a circuit for the load magnet independently of said last named resistance when the 70 automatic controller is operated.

In testimony whereof, I have signed my name to this specification in the presence of two subscribing witnesses.

JOHN D. IHLEDER.
